PANEL FRONT FOR A GRAPHICAL RECORDER

Edward E. Austin, Pasadena, and Richard M. Kemplin,
Los Angeles, Calif., assignors to F. L. Moseley Co., a corporation of California

Application May 17, 1957, Serial No. 46,212

Term of patent 14 years

(Cl. D52—1)

Fig. 1 is a perspective view of a panel front for a graphical recorder showing our new design; and

Fig. 2 is a side elevational view thereof.

We claim:

The ornamental design for a panel front for a graphical recorder, as shown.
